US00D968690S

(12) **United States Design Patent** (10) **Patent No.:** **US D968,690 S**
(45) **Date of Patent:** **** Nov. 1, 2022**

(54) **VAPORIZER DEVICE**

(71) Applicant: **Pax Labs, Inc.**, San Francisco, CA (US)

(72) Inventors: **David Carlberg**, Portland, OR (US); **Alexander Weiss**, Oakland, CA (US); **Alexander Ringrose**, Oakland, CA (US); **Devin Spratt**, Sunnyvale, CA (US); **Marko Markovic**, San Francisco, CA (US); **Robyn Nariyoshi**, San Francisco, CA (US); **Brandon Cheung**, San Francisco, CA (US); **Christopher Nicholas Hibmacronan**, Oakland, CA (US); **Joshua Morenstein**, San Francisco, CA (US); **John Hwang**, San Francisco, CA (US)

(73) Assignee: **Pax Labs, Inc.**, San Francisco, CA (US)

(**) Term: **15 Years**

(21) Appl. No.: **29/778,724**

(22) Filed: **Apr. 14, 2021**

Related U.S. Application Data

(62) Division of application No. 29/737,569, filed on Jun. 10, 2020, now Pat. No. Des. 919,881, which is a division of application No. 29/649,289, filed on May 29, 2018, now Pat. No. Des. 898,278.

(57) **CLAIM**

The ornamental design for a vaporizer device, as shown and described.

DESCRIPTION

FIG. 1 is a left side, front, and top perspective view of a vaporizer device of our design;

FIG. 2 is a rear, left side, and bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dash-dash broken lines illustrate portions of the vaporizer device that form no part of the claimed design.

1 Claim, 5 Drawing Sheets
